UNITED STATES PATENT OFFICE.

CHARLES E. WHEELER, OF FARMINGTON, MAINE.

DIP-NET FRAME.

SPECIFICATION forming part of Letters Patent No. 407,979, dated July 30, 1889.

Application filed March 1, 1888. Serial No. 265,984. (No model.)

To all whom it may concern:

Be it known that I, CHARLES E. WHEELER, a citizen of the United States, residing at Farmington, in the county of Franklin and State 5 of Maine, have invented new and useful Improvements in Dip-Net Rings and Staffs; and I do hereby declare the following to be a full, clear, and exact description of the invention, such as will enable others skilled in the art to 10 to which it appertains to make and use the same.

My invention relates to improvements in net ring or bow and staff to which nets may be attached for landing fish. This ring or bow is preferably made of flat spring-brass, 15 as follows:

Figure 1 shows the top ends of the ring or bow in two sections or parts, with socket A on the end of one bow, into which the other end of the bow slides, when the two parts 20 of the ring or bow are bent into ring or bow shape. The bottom of the two parts of the ring are made to fit the fork-shaped head B, upon which the two lower parts of the ring or bow C C' are loosely riveted or bolted to 25 each fork of the head in such manner as to allow the two sections or pieces of the ring or bow to freely turn back upon the staff II, Fig. 3, when so desired.

In Fig. 2 is shown the ring or bow with the 30 upper ends of the two sections or pieces joined together in the socket D. Upon and a part of the other end of the head E, Fig. 2, is a socket or ferrule to receive the hollow staff or handle of the dip-net, in which fishing-rod tips may be carried. Upon and around 35 the outside of this hollow socket or ferrule is a sliding ferrule or clamp with slots f f', Fig. 2, to receive and rigidly secure in place the two lower ends of the net ring or bow when 40 in use. When not in use, the sliding ferrule or clamp is designed to slide back upon the main ferrule, as shown at G, Fig. 3, thereby

releasing the lower ends of the ring or bow, so that the two parts of the ring or bow, when disconnected at the top socket D, Fig. 2, may 45 be turned back upon the staff or handle into slots h h', Fig. 3, made in or upon the staff to receive the upper ends of the ring or bow when turned on the rivets or bolts back onto the staff, thereby permitting the net and sec- 50 tional ring or bow to be reduced to a small compass for carrying in the hand or for shipment.

I claim as my invention—

1. In a folding dip-net ring or bow, the com- 55 bination of a ring or bow in two sections or pieces, with the two upper ends of the same connected and secured by a socket or slots around screw-heads, and the two lower ends of the ring or bow loosely riveted or bolted 60 to the sides of a forked or short-armed head in such manner that the two lower ends of the sections or pieces of the ring or bow, when disconnected at the upper socket, may be turned back on the loosely riveted or bolted 65 joints and rest in or upon slots on the sides of the staff or handle without removing the net from the rings or bows, thereby holding the said upper ends of the ring or bow in place upon the staff or handle, substantially 70 as described.

2. In a dip-net, the combination of a socket or ferrule on the staff thereof, a sliding collar on said socket provided with an integral tubular enlargement or offset for clamping 75 the inner extremities of the separable bows of said net, substantially as described.

In testimony whereof I affix my signature in the presence of two witnesses.

CHARLES E. WHEELER.
